UNITED STATES PATENT OFFICE.

GEORGE F. CLARKE, OF FENTON, MICHIGAN.

OIL-CUP FOR ENGINES.

SPECIFICATION forming part of Letters Patent No. 741,309, dated October 13, 1903.

Application filed July 30, 1902. Serial No. 117,645. (No model.)

To all whom it may concern:

Be it known that I, GEORGE F. CLARKE, a citizen of the United States, residing at Fenton, in the county of Genesee, State of Michigan, have invented certain new and useful Improvements in Oil-Cups for Engines; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an oil-cup for explosive-engines; and it consists in the construction and arrangement of parts herein-after fully set forth.

The object of the invention is to provide simple and efficient means for heating the oil in the oil-cup, so as to render it sufficiently fluid to readily feed into the cylinder even in extremely cold weather, thereby insuring perfect lubrication of the piston under all conditions.

The above object is attained by the association and arrangement of parts illustrated in the accompanying drawings, in which—

Figure 1 is an elevation of my improved oil-cup, showing its connection with the water-pipe leading from the jacket of the cylinder and its means for connection with the cylinder. Fig. 2 is a vertical section therethrough. Fig. 3 is a horizontal section as on line 3 of Fig. 2. Fig. 4 is a view, partly in section, showing the oil-cup connected with the cylinder and with the water-pipe which leads from the water-space around the cylinder.

In many instances where explosive-engines are used for stationary work they are located in an exposed position, so that in cold weather it is difficult to keep the oil sufficiently fluid to cause it to flow readily into the cylinder—a condition which sometimes results in the engine running dry.

By means of my improved oil-cup I am enabled at all times to maintain the oil at such a temperature as to insure a perfect feeding thereof into the cylinder under all conditions of temperature.

Referring to the characters of reference, 1

designates an oblong coupling having threaded apertures at its ends in which may be screwed the water-pipe 2, leading from the water-space 3, which surrounds the cylinder 4, the water being kept in constant motion through said space and the pipe 2 by a pump or other suitable means (not shown) for the purpose of keeping down the temperature of the cylinder, as is well understood in the art. Within the coupling 1 is a central core 5, having an oil-chamber 6 therein. Passing on either side of said core is a channel 7, which communicates with the pipe 2 at opposite ends of the coupling and establishes a passage-way for the flow of water through said coupling around said core. Mounted upon the upper face of the coupling 1 is a glass oil-cup 8, which is preferably cylindrical in form and which is closed by a cap 9, having interposed between it and the upper edge of the cup a gasket 10. The lower end of the cup is seated in an annular recess and rests upon the washer or gasket 11.

Depending from the cap 9 is a central tube 12, which extends downwardly through the cup and oil-chamber and is screwed at its lower end into a threaded opening at the bottom of said chamber. Formed in the wall of the tube 12 near its lower end is an oil-port 13, through which the oil passes from the chamber 6 into said tube. Screwed into a tapped opening in the under side of the coupling 1 and in vertical alinement with the tube 12 is a hollow nipple 14; through which the oil is adapted to flow. Passing downwardly through the tube 12 and into the nipple 14 is a needle-point valve 15, the stem 16 of which is threaded in the cap 9, so as to enable said valve to be adjusted to regulate the flow of oil through the nipple 14 by increasing or decreasing the distance between the point of said valve and its seat 17 within said nipple. After adjustment the valve may be secured by the lock-nut 18.

Below the nipple 14 is a sight-feed glass 19, through which the oil is adapted to pass and which is held in place by a surrounding annular casing 20, whose upper end is threaded to screw onto the threaded flange 21 of the nipple, the upper end of said glass bearing against the washer 22 and the lower end resting upon the washer 23, whereby the glass is

securely held in place and a tight joint is made between its ends and the connected parts. The lower end of the casing is provided with a threaded stem 24, adapted to screw into the cylinder, as shown in Fig. 3, and through said stem is an oil-discharge passage-way 25, which communicates with the port 26, leading into the cylinder. Formed in the casing 21 is a side opening 27, through which the glass 19 may be seen, enabling the engineer to note the feed of the oil as it drops from the nipple 14.

It will be understood that the passage of the water from the cylinder through the coupling 1 will heat the oil to a high state of fluidity, enabling it to freely pass from the oil-cup through the nipple 15 and into the cylinder. As there is a continuous flow of this heated water while the engine is in operation, there is no opportunity for the oil in the cup to become chilled, enabling this cup to be used upon engines that are situated in exposed places and insuring a perfect feeding of the oil in the coldest weather.

In the cap 9 is an oil-feed opening 28, through which oil may be introduced into the cup.

Having thus fully set forth my invention, what I claim as new, and desire to secure by Letters Patent, is—

1. In an oil-cup, the combination of a coupling having an oil-chamber therein, a water passage-way around said chamber, an oil-receptacle mounted on the coupling over said chamber and communicating therewith, a tube passing through the receptacle and chamber having an opening which communicates with the oil-chamber, a valve in said tube to regulate the flow of oil, and a pipe adapted to connect said water passage-way in said coupling with the water-space around the cylinder of an engine.

2. In a device for the purpose set forth, the combination of a pipe communicating with the water-space of a cylinder, a coupling in

said pipe having an oil-chamber, and a water-space surrounding said chamber, through which water is adapted to flow, and with the opposite ends of which said pipe is connected, an oil passage-way connecting the oil-chamber in said coupling with the interior of said cylinder, a sight-feed glass in said passage-way interposed between the coupling and cylinder, and a valve controlling the communicating oil-passage between said cylinder 55 and chamber.

3. The combination of a pipe adapted to communicate with the water-space of an explosive-engine cylinder, a coupling in said pipe having an oil-chamber therein around 60 which the water is adapted to flow, an oil-receptacle mounted upon the coupling and communicating with said oil-chamber; means connecting the oil-chamber of said coupling with the interior of said cylinder, a nipple through 65 which the oil is adapted to be discharged, and means for controlling the flow of oil through said nipple.

4. The combination of a coupling having an oil-chamber therein and a passage for water around said chamber, an oil-cup mounted on the coupling above said chamber, a cap closing said cup, a tube depending from said cap and screwing into an aperture at the bottom of said oil-chamber, an oil-opening in the 75 side of said tube, a nipple screwing into the under face of said coupling in alinement with said tube, a sight-feed glass around nipple, a casing holding said glass in place and establishing communication between the nipple and the interior of the cylinder, and a needle-valve passing through said tube and seating in said nipple.

In testimony whereof I sign this specification in the presence of two witnesses.

GEORGE F. CLARKE.
